SAFETY CONTROL AND IGNITION MEANS
FOR MULTIPLE GAS BURNERS

Earl W. Roberts and Thomas L. Ferrall, Detroit,
Mich., assignors to The Roberts Brass Manufacturing Company, Detroit, Mich., a corporation of Michigan

Application February 25, 1935, Serial No. 8,180

12 Claims. (Cl. 158—117.1)

The invention relates to safety control and ignition means for gas ranges, including open top and oven burners. It is one of the objects of the invention to obtain a construction containing a plurality of pilots for different burners in which the extinguishing of any one of said pilots will shut off the gas supply, not only to the burners but to the pilots also. It is a further object to combine with this structure means for quickly lighting the extinguished pilots and after a brief interval automatically opening the gas supply to the burners. Still another object is to facilitate the lighting of the oven burner by locating the pilot therefor within the oven while at the same time guarding against any escape of unignited gas which might form within the enclosure an explosive mixture. With these and other objects in view the invention consists in the construction as hereinafter set forth.

In the drawings:

Fig. 1 is a plan view of a gas range to which our improvements are applied;

Fig. 2 is a diagrammatic side elevation illustrating the connections between the several elements of the structure;

Fig. 3 is a perspective view of the oven ignition and control unit;

Fig. 4 is a sectional side elevation of the automatic shut-off valve and its actuating mechanism;

Fig. 5 is a longitudinal section on line 5—5, Fig. 3;

Fig. 6 is a section through the push button control valve.

The gas range to which our improvements are applicable may be of any suitable construction including an open top section A having a plurality of burners B, B', B², B³ and an oven section C provided with a burner D. E is a gas supply conduit shown as extending across the open top section intermediate the pairs of burners B, B' and B², B³. F is a manifold to which the conduit E is connected; G, G', G² and G³ are the valves for the burners B, B', B², B³, and H is a valve controlling the oven burner D.

I is an automatic shut-off valve located in the supply conduit E and controlling the supply of gas to all of the burners. Mounted on the casing I' of the valve I so as to form a unit construction therewith is a pilot burner J, a thermal motor K and a connecting mechanism between said motor and the valve I. The thermal motor is preferably a U-shaped bar, one leg of which is secured to a bracket J' on the pilot burner J by means of screws J² and the bend in the U is located directly

above the flame of the pilot so that the latter will impinge thereon. The free leg of the U is connected by a link L with a bell crank lever L' fulcrumed upon a bracket L² which is integral with the cap L³ for the valve casing I' and which also forms the support for the burner J. The stem I² of the valve I extends outward through the cap L³ and at its outer end is engaged by an adjustable screw L⁴ on the bell crank lever L'. The arrangement is such that the heat of the pilot flame on the bend of the U-shaped member K will move the free leg thereof outward, transmitting this movement through the link L to the bell crank lever L' and from the latter through the screw L⁴ to the stem I², forcing this inward and separating the valve I from its seat. A spring I³ within the valve casing opposes this moving of the valve and operates upon the extinguishing of the pilot and cooling of the member K to again force the valve I to its seat. The pilot J also forms the lighter for the burners B, B', B², B³ and to this end the pilot is enclosed in a cylindrical casing J³ having radiating tubes J⁴ extending in proximity to the respective burners and adapted to receive gas therefrom. Thus upon the turning on of any one of these burners gas will travel through the tube J⁴ to the pilot and the flame will flash back to the burner to light the same.

The oven burner D is lighted from a second pilot burner M which is mounted on a bracket M' secured within the oven to a side wall thereof. A thermal motor M² similar to the thermal motor K has one leg thereof secured to the bracket M' with the bend of the U located above the flame of the pilot. The bracket M' is also provided with a shelf portion M³ on which is pivoted a bell crank lever M⁴. M⁵ is a tubular bearing on the shelf M³ which extends outward through an aperture in the oven wall. This bearing is internally threaded to engage a correspondingly threaded portion of a valve casing N located outside of the oven. Within the casing N is a valve N' having a stem N² extending axially through the portion of the casing within the bearing M⁵ into operative relation to the bell crank lever M⁴ so that a movement of the latter will unseat the valve. N³ and N⁴ are nipples on the valve casing N communicating with chambers within said casing on opposite sides of the seat so that the unseating of the valve will establish communication from one nipple to the other. The nipple N³ is connected by a conduit O to the manifold F. The nipple N⁴ is connected to a branch fitting O', one branch of which is connected by a conduit O' to the pilot M.

- while the other branch is connected by a conduit O³ to a branch fitting O⁴. One branch of fitting O⁴ is connected by a conduit O⁵ with the pilot J, while the other branch is connected to the casing 5 of a push button valve P. Connected to this casing on the opposite side of the valve is a conduit P' which extends to the casing I' of the valve I and is connected to the gas supply side of the valve.
- 10 With the construction and arrangement of parts just described it will be observed that all of the main burners and also the pilot burners are normally supplied with gas from the manifold F, which latter receives gas from the supply conduit E whenever the valve I is in open position. However, the opening of this valve is dependent upon the operation of the pilot J and the thermal motor K actuated thereby. Consequently to start operation gas must be supplied to 15 the pilots from a separate source, viz: through the conduit P' to the push valve P. Upon operation of this valve P gas will pass through the branch fitting O⁴ and conduit O⁵ to the pilot J and through the other branch of the fitting O⁴, conduit O³, branch fitting O' and conduit O² to the pilot M. Thus both of the pilots may be lighted and after burning for a short interval of time will operate with their cooperating thermal motors K and M² to respectively open the 20 shut-off valve I and the valve N'. This will supply gas to the manifold F and from the latter through the conduit O past the open valve N' to the branch fitting O' from which gas passes to each of the pilots to maintain operation there- 25 of after the push button is released and its valve closed.

As has been stated, the pilot M is located within the oven and is utilized for lighting the oven burner D. As the closing of the oven door will 30 sometimes create sufficient disturbance in the atmosphere to extinguish the pilot, we have surrounded the jet by a frusto-conical shield M³ which protects the flame. The oven burner is lighted from the pilot through suitable means, 35 such as a perforated extension tube or trailer projecting from said oven burner into proximity to the flame of the pilot. Thus when gas is supplied to the oven burner, flame will flash thereto from the pilot through the comparatively short 40 distance therebetween. Such an igniter has an advantage over those of a type in which the pilot is located outside the oven, as the longer transfer tube required by this arrangement is sometimes rendered inoperative by grease deposits in- 45 cident to the cooking of food in the oven. It is necessary, however, with such construction to avoid danger of forming an explosive mixture in the oven in case of the extinguishing of the pilot. With our construction such danger is avoided as 50 the extinguishing of the pilot will cause the closing of the valve N' which cuts off gas supply to the pilot J, and this in turn results in the closing of the shut-off valve I. The response to the thermal motors is sufficiently rapid so that if the 55 pilot within the oven is extinguished the supply of gas thereto will be soon cut off.

What we claim as our invention is:

1. In combination, a gas manifold, a supply conduit therefor, an automatic valve controlling the supply of gas from the conduit to the manifold, two pilots, a second automatic valve, means for conducting gas from the manifold to said second automatic valve, means for conducting gas from said second automatic valve to said pilots, means for conducting gas from said conduit on

the supply side of said first automatic valve to the second mentioned conducting means, a normally closed push button valve controlling the passage of gas from the third to the second mentioned conducting means, and means responsive to the heat of said pilots and operatively connected to said automatic valves for controlling the action of said automatic valves.

2. In combination, a gas manifold, a supply conduit therefor, an automatic valve controlling the supply of gas from the conduit to the manifold, two pilots, a second automatic valve, means for conducting gas from the manifold to said second automatic valve, means for conducting gas from said second automatic valve to said pilots, means for conducting gas from said conduit on the supply side of said first automatic valve to the second mentioned conducting means, a normally closed push button valve controlling the passage of gas from the third to the second mentioned conducting means, means responsive to the heat of one of said pilots for controlling the action of the second mentioned automatic valve, and means responsive to the heat of the other pilot for controlling the action of the first mentioned automatic valve.

3. In combination, a gas manifold, a conduit for supplying gas to said manifold, an automatic valve controlling the flow of gas through the conduit to the manifold, two gas pilots, a constantly open conduit extending between said pilots, a conduit for conducting gas from the manifold to the second mentioned conduit, and an automatic valve in the third mentioned conduit for controlling the flow of gas from the third mentioned conduit through the second mentioned conduit to said pilots.

4. In combination, a gas manifold, a conduit for supplying gas to said manifold, an automatic valve controlling the flow of gas through the conduit to the manifold, two gas pilots, a constantly open conduit extending between said pilots, a conduit for conducting gas from the manifold to the second mentioned conduit, an automatic valve in the third mentioned conduit for controlling the flow of gas from the third mentioned conduit through the second mentioned conduit to said pilots, a conduit for conducting gas from the first mentioned conduit upon the supply side of the first mentioned automatic valve to the second mentioned conduit, and a manually operable valve in the fourth mentioned conduit for controlling the supply of gas from the first mentioned conduit to the second mentioned conduit.

5. In combination, a gas manifold, a conduit for supplying gas to said manifold, an automatic valve controlling the flow of gas through the conduit to the manifold, two gas pilots, a constantly open conduit extending between said pilots, a conduit for conducting gas from the manifold to the second mentioned conduit, an automatic valve in the third mentioned conduit for controlling the flow of gas from the third mentioned conduit through the second mentioned conduit to said pilots, and means responsive to the heat of said pilots for opening the automatic valves.

6. In combination, a gas manifold, a conduit for supplying gas to said manifold, an automatic valve controlling the flow of gas through the conduit to the manifold, two gas pilots, a constantly open conduit extending between said pilots, a conduit for conducting gas from the manifold to the second mentioned conduit, an automatic valve in the third mentioned conduit for controlling

- the flow of gas from the third mentioned conduit through the second mentioned conduit to said pilots, a conduit for conducting gas from the first mentioned conduit upon the supply side of the first mentioned automatic valve to the second mentioned conduit, a manually operable valve in the fourth mentioned conduit for controlling the supply of gas from the first mentioned conduit to the second mentioned conduit, and means responsive to the heat of said pilots for opening the automatic valves. 5
7. In combination, two gas pilots, a constantly open conduit extending between said pilots, a gas manifold, a conduit for supplying gas to said manifold, an automatic valve responsive to the heat of one of said pilots for controlling the flow of gas through the second mentioned conduit to the manifold, a conduit for conducting gas from the manifold to the first mentioned conduit, and an automatic valve in the third mentioned conduit responsive to the heat of the other pilot for controlling the flow of gas from the third mentioned conduit through the first mentioned conduit to said pilots. 10
8. In combination, two gas pilots, a constantly open conduit extending between said pilots, a gas manifold, an automatic valve in constantly open communication with said manifold and connected to said conduit for controlling the supply of gas to said pilots, a supply conduit for the manifold, an automatic valve controlling the flow of gas through the supply conduit to the manifold, a manually operable valve in constantly open communication with the supply conduit on the supply side of the second mentioned automatic valve, and means responsive to the heat of said pilots for opening the automatic valves. 15
9. In combination, two gas pilots, a constantly open conduit extending between said pilots, an automatic gas valve in constantly open communication with a source of gas supply and connected to said conduit for controlling the supply of gas to both said pilots, a manually operable valve in constantly open communication with a source of gas supply and connected to the conduit extending between said pilots, so that upon manipulation of said manually operable valve gas from the second mentioned source may be temporarily supplied to both pilots to permit them to be lighted, and means responsive to the heat of one of said pilots for opening the automatic valve so gas from the first mentioned source may be supplied to both of said pilots. 20
10. In combination, two gas pilots, a constantly open conduit extending between said pilots, an automatic gas valve in constantly open communication 25
- cation with a source of gas supply and connected to said conduit for controlling the supply of gas to both of said pilots, a push button valve in constantly open communication with a source of gas supply and connected to the conduit extending between said pilots so that upon actuation of said push button valve gas from the second mentioned source may be temporarily supplied to both pilots to permit them to be lighted, and means responsive to the heat of one of said pilots for opening the automatic valve so gas from the first mentioned source may be supplied to both of said pilots. 30
11. In combination, a gas manifold, a conduit for supplying gas to said manifold, a shut-off valve in said conduit biased to automatically close, a thermal motor for opening said valve, a gas pilot operatively associated with said thermal motor to actuate the same, means for conducting gas from the manifold to said pilot, a shut-off valve in said conducting means biased to automatically close, a thermal motor for opening the second mentioned shut-off valve, a gas pilot operatively associated with the second mentioned thermal motor to actuate the same, and means on the delivery side of the second mentioned shut-off valve for conducting gas from the first mentioned conducting means to the second mentioned pilot. 35
12. In combination, a gas manifold, a conduit for supplying gas to said manifold, a shut-off valve in said conduit biased to automatically close, a thermal motor for opening said valve, a gas pilot operatively associated with said thermal motor to actuate the same, means for conducting gas from the manifold to said pilot, a shut-off valve in said conducting means biased to automatically close, a thermal motor for opening the second mentioned shut-off valve, a gas pilot operatively associated with the second mentioned thermal motor to actuate the same, means on the delivery side of the second mentioned shut-off valve for conducting gas from the first mentioned conducting means to the second mentioned pilot, means for conducting gas from the conduit on the supply side of the first mentioned shut-off valve to the first mentioned conducting means on the discharge side of the second mentioned shut-off valve, and a normally closed valve in said third mentioned conducting means operable when the first mentioned shut-off valve is closed to permit gas on the discharge side of the second mentioned shut-off valve to be bypassed from said conduit to said pilot burners. 40
